UNITED STATES PATENT OFFICE.

ARNO H. HOPFNER, OF CARLSTADT, NEW JERSEY.

CIRCUIT CLOSER.

Application filed June 8, 1926. Serial No. 114,390.

The main object of this invention is to provide a circuit closer which is used in combination with an alarm clock for the purpose of closing a circuit automatically at a predetermined time so that a filament lamp illuminates a chamber or room at the time desired. This invention is particularly useful at the waking hour, at which time the shaft of the spring drum of an alarm clock 5 rotates and the circuit closer coupled to this spring drum shaft is released when said shaft makes a half turn. A lever falls and closes the circuit thru a filament lamp which is thereby illuminated and remains so until 10 the circuit is again opened by a switch.

The above and other objects will become apparent in the description below, in which characters of reference refer to like-named parts in the drawing.

Referring briefly to the drawing, Figure 1 is a perspective view of the circuit closer, showing its cooperation with an alarm clock.

Figure 2 is a top plan view of the circuit closer with the cover removed and showing 20 the electrical circuit schematically.

Figure 3 is a sectional elevational view taken on line 3—3 of Figure 2.

Referring in detail to the drawing, the numeral 10 indicates a panel which serves 30 as a base for the circuit closer. The circuit closer consists of a housing having side walls 11 and 12 and end walls 13 and 14 which latter join the side walls. These walls form a chamber 15 in which the entire circuit closer mechanism is located. The chamber 35 15 is entirely enclosed by a cover 16 which may be secured in place in any desirable manner. The side walls 11 and 12 of the housing are provided with apertures intermediate their length in which sockets 17 and 40 18 are fixedly inserted. These sockets are secured in place as desired and are provided with rectangular channels 19 into which the plug pins of complementary plug sockets 20 are inserted. A lead 21 connects in series the terminals of both sockets 17 and 18. The remaining terminals of each of these 45 21 and 18 has a wire 22 leading from its respective plug to individual terminal plates 23 and 24. These terminal plates have upstanding fingers 25 which are separated from each other by a gap. A pair of ears 26 and 27 are mounted within the chamber 15 and are spaced-apart from each other. In the space between the ears 26 and 50 27, one end of a substantially horizontal lever

28 is pivoted. Said lever is superimposed over the fingers 25 and the lever is provided with a pintle 29, conical in shape, over its fingers so that when said lever is lowered, 55 the pintle contacts with both fingers and closes the gap therebetween. This lever is constructed of some insulating material such as bakelite and its free end extends out of the housing thru a vertical slot 30 formed 60 in the wall 13. Said extending end has an arm 31 rigid therewith and from said arm an adjustable bar 32 extends. This bar is fastened in place by a wing bolt 33 which permits adjustment of the bar 32 with respect to the arm 31. The end of the bar 32 65 has a balled head 34 thereon which is adapted to fit into a hemispherical socket 35 formed in the outer end of a coupling block 36. Said coupling block is provided with 70 slots 37 and 38 which slip over the wing of a wing bolt 40, the latter being used to tense 75 the spring drum of the alarm mechanism of an alarm clock 41.

The two wires 42 and 43, which are connected to the plug socket 20, are joined by a switch 44. The two wires which extend from the remaining socket 20 lead to one plug of a three-way socket thru the leads 45 and 46. The lead 46 emerges from the three-way 80 socket and communicates with the plug lead of a lighting circuit and the opposite lead wire 45 passes thru the remaining plug 47 thru a filament lamp 48 which is in series 85 circuit with the wire 45 and then passes to the minus lead of the electrical circuit.

In using the circuit closer, the block 36 is mounted on the wing nut, as shown in Figure 1, by permitting the wing portion 39 of member 40 to enter into the slots 37 in such manner that the socket 35 is open at the top. Before this is done, however, the spring drum actuating the alarm mechanism of the clock is tensed. The balled head 34 mounted at the end of the bar 32 is then inserted into the socket 35. The lever, when inserted into the socket, should be in lifted position out of contact with the fingers 25 so that the circuit thru the lamp 42 is open. One of the 90 21 plugs 20 which has the switch 44 in circuit therewith is plugged into the socket 17 and the switch fixture is carried to any part of the room in which it is used. The remaining member 20 is plugged into the socket 18, thus connecting the electrical circuit leads indicated by the symbols plus and minus with the circuit closer. When the predetermined 95 100 105 110 115

time to which the alarm clock has been set has arrived, the alarm mechanism is actuated by being tripped in the usual manner, and as this is being done, the spring drum begins 5 to rotate, carrying with it the wing 39 of member 40. This causes the blocks 36 to be rotated, and when it is rotated 180 degrees, the open end of the socket 35 is at the bottom of the block 36 and permits the balled 10 head 34 to fall out of the socket downwardly so that the pintle engages both tongues 25 and causes the circuit to be closed to illuminate the lamp 48, for which purpose the device is constructed. The circuit closer is particularly useful during the waking hour, and 15 after the user is awakened, he may, if desired, open the circuit by operating the switch 44.

It is to be noted that certain changes in 20 form and construction may be made without departing from the spirit and scope of the invention.

I claim:—

1. In the combination of an alarm clock 25 and a circuit closer, a lever extending from

said circuit closer, a balled head rigid at the free end of said lever, means mounted on the alarm mechanism of said clock comprising a slotted block, and means in said block for supporting the balled end of the lever in 30 raised position.

2. In the combination of an alarm clock and a circuit closer having a lever extending from said circuit closer, a balled head at 35 the free end of said lever, means mounted on the alarm mechanism of said clock engageable with said balled head for holding said lever in raised position comprising a slotted block, a hemispherical socket in said block normally receiving said balled end of said lever, said block when rotated 180 degrees being adapted to reverse the open portion 40 of said socket and permit falling of said balled end of said lever to close a circuit, and means for adjusting the alignment of 45 said lever.

In testimony whereof I affix my signature.

ARNO H. HOPFNER.
